UNITED STATES PATENT OFFICE.

JACOB B. BLOW, OF PITTSBURG, PENNSYLVANIA, ASSIGNOR TO BLOW COLLAPSIBLE STEEL CENTERING COMPANY, OF PITTSBURG, PENNSYLVANIA, A CORPORATION OF NEW JERSEY.

CEILING-MOLD.

No. 853,957.

Specification of Letters Patent.

Patented May 21, 1907.

Application filed November 12, 1906. Serial No. 343,010.

To all whom it may concern:

Be it known that I, JACOB B. BLOW, a citizen of the United States, residing at Pittsburgh, in the State of Pennsylvania, have invented certain new and useful Improvements in Ceiling-Molds, of which the following is a specification.

My invention relates to molds for concrete ceilings, and has for its objects; to produce a mold which can be readily released from the concrete; to produce a mold which shall be when in position for molding, very stiff and unyielding; and finally, to provide a mold of minimum weight and great simplicity which shall be of more durable construction and less expensive than the wooden molds now in use. One embodiment of my invention is illustrated in the accompanying drawing in which the figure is a transverse section through the mold and the concrete.

My mold is preferably constructed of thin sheet metal which can be easily handled, and furthermore can be detached from the concrete after it has set, by a gradual or peeling action, and without hammering or jarring which has a tendency to crack the concrete. Heretofore wooden molds have been used for the concrete, but such molds fail to produce a smooth surface, are detached with difficulty, are cumbersome and expensive, and can be used only a few times. My mold on the other hand, produces a smooth surface, can be detached easily, is cheap and practically indestructible.

Referring to the drawing, 1, 2 and 3 are arched plates of thin flexible sheet metal of any desired length convenient for handling, 4 are butt straps for joining the arched plates together, which butt straps are riveted to the plates 2 and 3 and secured to the opposing plates by means of the loops 5 fastened to the plates 1 and 2 and extending through slots in the butt plates, in which position they are held by means of short wedges in a manner well known in the art. The various plates are stiffened by means of the transverse turnbuckles 6, which turnbuckles are secured to the plates by means of the angles 7, which angles are provided with holes for the reception of the bent ends of the turnbuckles. The turnbuckles not only serve to stiffen the arched members, but also serve to

collapse them after the concrete has set and it is desired to remove the molds to a new position. In operation the mold member may be supported adjacent the butt straps 4 either by means of temporary pillars or posts from the floor beneath, or by means of members extending down from the I-beams 8 which constitute the frame-work of the ceiling. After the concrete has set, the supports adjacent the butt straps are removed, the holding wedges drawn from the loops 5, and the arches are collapsed one at a time by means of the turnbuckles. 55 60 65

It will be seen from the foregoing that by using a plurality of arched plates, a mold of ample stiffness can be made out of material so thin that if flat it would sag with the slightest weight, and further, because of the small size of the arches each may be collapsed with slight difficulty. It will also be noted that the arches add to the ornamental appearance of the ceiling. 70

Having thus described my invention and illustrated its use, what I claim as new and desire to secure by Letters Patent, is the following:

1.-In combination, a ceiling mold composed of flexible material and comprising a plurality of arched plates detachably secured together at their edges and having stiffening and collapsing braces. 75 80

2.-In combination, a ceiling mold composed of flexible material and comprising a plurality of arched plates detachably secured together at their edges and having transverse stiffening and collapsing braces engaging the plates near their edges. 85

3. In combination with a ceiling mold composed of flexible material and comprising a plurality of arched plates having their adjacent edges out turned, of fastening means for holding the out turned edges in alinement, and stiffening and collapsing 90 95 braces for the arches.

In testimony whereof I have hereunto signed my name in the presence of the two subscribed witnesses.

JACOB B. BLOW.
